(Cl. D3—25)

To all whom it may concern:

Be it known that I, Seymour F. Dennis, a citizen of the United States of America, residing at 325 East 57th Street, in the county of New York and State of New York, have invented a new, original, and ornamental Design for a Sport Shirt, of which the following is a specification, reference being had to the accompanying drawing, forming a part thereof. This application is a continuation in part of my earlier application, Serial No. D. 8,147 filed February 25, 1950.

Figure 1 is a front view of my novel sport shirt.

Figure 2 is a rear view of my novel sport shirt.

My design comprises a woven pull-over sport shirt having a two-toned body portion and set-in sleeves which match the upper side edges, collar and neck opening and contrast with the main body portion, the edges of the contrast being

further set-off by knitted bands at the upper sides and at the neckline, all as shown.

I claim:

The ornamental design for a sport shirt, as shown and described.

SEYMOUR F. DENNIS.
